UNITED STATES PATENT OFFICE.

DANIEL M. WRIGHT, OF HARTFORD, CONNECTICUT.

DIEING-MACHINE.

1,270,913.

Specification of Letters Patent.

Patented July 2, 1913.

Application filed January 10, 1917. Serial No. 141,595.

To all whom it may concern:

Be it known that I, DANIEL M. WRIGHT, a citizen of the United States, residing at Hartford, in the county of Hartford and State of Connecticut, have invented a new and Improved Dieing-Machine, of which the following is a specification.

My invention relates especially to that class of machines in which two dies are brought together to form to predetermined shape a device located between them, such machines being designed to exert great pressure of the dies one upon the other, and which machines are commonly designated by shop terms as power presses, and an object of my invention, among others, is to provide a machine of this class that shall be particularly steady and efficient in its operation, and one embodying in its structure a minimum amount of metal with a maximum amount of strength.

One form of machine embodying my invention, and in the construction and use of which the objects herein set out, as well as others, may be attained, is illustrated in the accompanying drawings, in which—

Figure 1 is a view in vertical section through the machine on plane denoted by dotted line 1—1 of Fig. 2.

Fig. 2 is a view in vertical section through the machine on plane denoted by dotted line 2—2 of Fig. 1.

The dies employed in dieing machines commonly have coöperating surfaces one of which usually comprises a matrix, and it is, therefore, essential that such dies shall be moved one toward the other in right lines and without other movement, as if such other movement takes place the dies will not properly register and they, therefore, become quickly dulled or worn out. This objectionable movement may be very slight, to produce the injurious results above described, and in fact the spring of the metal of which the frames of the machines are constructed may be sufficient to cause this objectionable action.

The machine illustrated and described herein is constructed to eliminate the objectionable features hereinabove set out, the structure in fact being such that the weight of metal comprising the frame may be reduced, the parts being so arranged and disposed one with respect to another that extreme steadiness in the movement of the dies is obtained and with practically no move-

ment thereof except in right lines one toward the other. The frame of my improved machine, as embodied in the illustration herein, comprises two ends 5 having flanges 6 as a means of providing steady support, said ends having cross bars 7 at the front and rear sides of the frame, said ends being of a height sufficient to support a table 8 at the proper distance from the floor to be readily accessible by a workman, and the frame comprising the ends, cross bars and table preferably being composed of a single piece of metal cast to shape. Openings 9 are formed through the ends and boxes 10 are secured to the under side of the table in position to support a main driving shaft 11 that projects through said opening and has a driving pulley 12 loosely supported on its outer end, and being adapted for connection with the shaft by means of a clutch 13. This clutch may be of any well known form of construction whereby, upon downward movement of the treadle 14 by the foot of the operative, the rod 15 is drawn downwardly and the clutch parts are operated to connect the driving pulley or fly wheel with the shaft, and upon one complete revolution of the shaft the clutch will be automatically disengaged from the driving pulley, the latter being usually driven as by means of a belt.

The shaft 11 is provided with a crank 16 at about its lengthwise center and of any ordinary form, said crank being connected by a rod 17 with a reciprocating support 18, the end of the rod being journaled upon a pin 19 secured within said support. The rod may be provided with any ordinary means for changing its length, as an adjusting screw 20 having threads of different character on opposite ends fitting within sleeves 21 and 22 journaled upon the crank 16 and pin 19 respectively. A flange 23 upon the screw is provided with suitable means to receive a spanner wrench by means of which it may be turned, and lock nuts 24 are employed to secure the screw against accidental turning movement, in addition to bolts 31 extending through the split sleeves 21 and 22.

The cross bars 7 are provided at opposite ends with steps 25 within which guide openings extending through the steps and into the cross bars are formed, and guide posts 26 projecting from the support 18 extend into these openings and serve as a means for

guiding and steadyng the movement of said support. Columns 27 are firmly secured to opposite corners of the support, which is preferably of substantially rectangular form when viewed in plan, said columns, of any desired number, extending through the table 8, the openings through which being preferably formed and equipped to receive the columns and guide 10 their movements therein. As shown in the drawing the posts 26 and columns 27 are formed as to one set of each, of a single piece or rod extending through the support and secured by the aid of nuts on opposite 15 sides of the support. A die holder 28 is secured to the upper ends of the columns and bears a die 29 positioned to coöperate with the die 30 on the table 8.

It will be readily appreciated that the 20 weight of my improved machine is located at the bottom thereof and below the lower die. The dies are located and move substantially in the line of application of power transmitted from the support 18 to the die 25 holder 28, so that there is no chance for any tipping or lateral movement of either of the dies, and the frame is so constructed that there can be no springing of the metal in this application of power whereby the dies 30 may be caused to get out of alinement to any extent.

The table supporting the dies being located at the top of the machine, the work is exposed to full light and the workman may 35 readily see what he is doing. The adjustment of the dies becomes a particularly simple matter and the chances for injury to the workman are thus greatly reduced. The machine, therefore, has the highest efficiency 40 in the performance of work requiring the application of immense power in machines of this class.

In accordance with the provisions of the patent statutes, I have described the principles of operation of my invention, together 45 with the apparatus which I now consider to represent the best embodiment thereof; but I desire to have it understood that the apparatus shown is only illustrative, and 50 that the invention can be carried out by other means.

I claim—

1. A dieing machine comprising a frame including a table adapted to receive a die, 55 a single member adapted to have a reciprocating movement with respect to said die, a single means for reciprocating said member, a plurality of supports exceeding two in number projecting from and rigid with said reciprocating member and guided in said frame, and a die holder rigidly secured to 60 said supports and adapted to receive a die to act in connection with the die on the table.

2. A dieing machine comprising a frame

including a table adapted to receive a die, a single member located for reciprocating movement underneath said table, a single means for reciprocating said member, a plurality of supports exceeding two in number 70 rising from and rigid with said reciprocating member and passing through openings in said table that constitute guides for said supports, and a die holder rigidly secured to said supports above said table and adapted to receive a die to coact with the die upon said table.

3. A dieing machine comprising a frame including a table adapted to receive a die, a single member located for reciprocating movement underneath said table, an eccentrically formed member located underneath the table, a single connection between said eccentrically formed member and said reciprocating member, a plurality of supports 80 exceeding two in number rising from and rigid with said reciprocating member and passing through guide openings in said table, and a die holder rigidly secured to said supports and adapted to receive a die to act 90 in connection with the die on said table.

4. A dieing machine including a frame whose top comprises a table adapted to receive a die, a single supporting plate mounted for reciprocating movement underneath 95 said table, a single means for reciprocating said plate, a plurality of columns exceeding two in number rising from and rigid with said plate and passing through guide openings in said table, and a die holder rigidly secured to said supports above said table and adapted to receive a die to act in connection with the die on said table.

5. A dieing machine including a frame whose top comprises a table adapted to receive a die, a single plate mounted for reciprocating movement underneath said table, an eccentrically formed member located underneath the table and above said plate, a single connection between said member and 105 said plate for reciprocating the latter, a plurality of supporting columns exceeding two in number rising from and rigid with said plate and extending to a location above said table, and a die holder rigidly secured 110 to said supporting columns above said table and adapted to receive a die to act in connection with the die on said table.

6. A dieing machine comprising a frame including a table adapted to receive a die, a single member having a reciprocating movement with respect to said die, a single means for reciprocating said member, a plurality of supports exceeding two in number projecting from one side of said reciprocating member and rigid therewith, guide members projecting from the side of said member opposite said supports, guides for said guide members, and a die holder rigidly secured to said supports and adapted 120 to receive a die to act in connection with the die on said table.

125

130

to receive a die to act in connection with the die on said table.

7. A dieing machine comprising a frame including a table adapted to receive a die, 5 a member mounted for reciprocating movement underneath said table, a single means for reciprocating said member, a plurality of supports exceeding two in number rising from and rigid with said reciprocating 10 member and extending through guide openings in the frame to a location above said table, a die holder rigidly secured to said supports and adapted to receive a die to act in connection with the die on said table, and 15 a plurality of guide members projecting from the side of said reciprocating member opposite said supports and extending into guide openings in said frame.

8. A dieing machine comprising a frame 20 including a table located at the upper part of the same adapted to receive a die and provided with rests at the lower part thereof, a supporting plate mounted for reciprocating movement underneath said table, 25 an eccentrically formed member mounted underneath said table and above said plate, a single connection between said member and said plate, a plurality of supports exceeding two in number rigid with and rising 30 from said plate to a location above said table, a die holder rigidly secured to said supports and adapted to receive a die to act in connection with the die on said table, and guide members projecting from the side 35 of the plate opposite the columns and extending into guide openings in said rests.

9. A dieing machine comprising a frame having a table at the top thereof adapted to receive a die and provided with rests, a 40 plate mounted for reciprocating movement underneath said table, a single means for reciprocating said plate, a plurality of columns exceeding two in number rigid with and extending through said plate and on

opposite sides thereof, portions of said columns being extended through and above the table and portions thereof being extended downwardly into openings in the rests for the frame, and a die holder rigidly secured to said supports and adapted to receive a 50 die to act in connection with the die on said table.

10. A dieing machine including a frame having a table at the top thereof adapted to receive a die and provided with openings 55 in the lower part thereof, a plate mounted for reciprocating movement underneath said table, an eccentrically formed member located between said table and said plate, a single operative connection between said 60 member and said plate to reciprocate the latter, a plurality of rods exceeding two in number extending through said plate and rigid therewith, portions of said rods being extended into the openings in the lower 65 part of the frame to afford guides for said plate, and portions of said rods being extended through and to a location above said table, and a die holder rigidly secured to said supports and adapted to receive a die 70 to act in connection with the die on said table.

11. A dieing machine including a frame whose upper portion provides a table adapted to receive a die, a driving shaft journaled 75 transversely of and in said frame beneath the table and having an eccentric member substantially midway between its ends, a reciprocable plate beneath said table having a single connection with said member, a 80 plurality of supports exceeding two in number rigid with said plate and each extending upwardly from a different portion thereof through guide openings in the frame to a location above the table, and a die holder 85 rigidly secured to the upper ends of said supports.

DANIEL M. WRIGHT.
